(57) **CLAIM**

The ornamental design for a head strap, as shown and described.

DESCRIPTION

FIG. 1 is a perspective view of a head strap showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the head strap where the head strap is in a configuration of use.

The broken lines in the FIGS. 1-8 depict portions of the head strap that form no part of the claimed design. The other broken lines in the FIG. 9 represent environment subject matter only and form no part of the claimed design.
